BELT FOR PAPER-FINISHING MACHINES.

Original application filed April 20, 1914, Serial No. 833,270. Divided and this application filed April 17, 1920. Serial No. 374,531.

The present invention relates to improvements in fabric belts for use in paper finishing machines, wherein paper is given a linen or other finish by being subjected to pressure between fabric surfaces.

It has for its object the provision of an endless belt which will present a smooth and unblemished surface to the paper, so that no marks or injuries will be received by the paper during the pressing action.

This application is a division of an application filed by us April 20, 1914, Serial No. 833,270, pursuant to which Patent No. 1,352,611 was granted September 14, 1920, for paper finishing machine, to which reference is made for a complete description of the machine in which our improved belt is designed for use.

As is stated in that application, in the preparation of high-grade finished paper, it is customary to use a "plater", comprising a pair of rolls together with means for forcing them together with great pressure and simultaneously rotating them. In this process the paper is dealt with only in sheets, which are built up with certain sheets of other material into what is termed a "book", which is then run between the rolls of the plater. The book comprises a sheet of thin metal, such as zinc, then a sheet of linen, then metal, then linen, paper, linen, and metal, and so forth. The book so made up is usually passed a number of times backwards and forwards between the rolls. In this operation, the pattern of the linen is transferred to the paper, and, in consequence of the slip which inevitably occurs between the various sheets, a polish is given to the surface of the paper.

This process gives good results, but is laborious, slow, and expensive. In the application above referred to, we have disclosed a machine adapted to produce the same result by continuous operation. A web of paper (although sheets can be used as well) is fed between coating pressure rolls over which belts of linen or other finishing material are led. One pressure roll is made of resilient material, so that the belts will not be damaged, and so that a slight amount of slip will occur between the belts and the paper, as is all fully set forth in the appli-

cation above referred to. The invention which this application is designed to cover relates to the construction of these belts.

It can readily be seen that, under the heavy pressure exerted between the pressure rolls, every blemish or irregularity in the belts will be faithfully reproduced in the surface of the paper. This will be the more serious as, owing to the belts being endless, the same imperfection will be reproduced over and over again on the web of paper which is being treated.

One form of irregularity or blemish that is independent of the perfection of the material of which the belt is made is the joint where the two ends of the strip material are joined to make an endless belt. It may, of course, be possible to construct a belt woven in endless form and having no joints, but, in any event, this would require special machinery and would be very expensive. Our invention is directed specifically to the provision of a joint which will present no blemishes or irregularities at this point of the belt and which will not mar nor injure the paper when it comes in contact therewith.

In order to give a clear view of the use for which this belt is intended, the machine in which it is used will be briefly described. Reference will now be made to the accompanying drawings, in which—

Fig. 1 is a vertical longitudinal section of a paper finishing machine in which a belt made according to our invention is designed for use;

Fig. 2 is a fragmentary longitudinal section of a belt embodying our invention; and

Fig. 3 is a plan view of the same, the upper ply of the belt being shown as broken away at the left.

In the form of machine illustrated in Fig. 1, the paper to be finished is fed from a reel 10, over a guide roll 11, between pressure rolls 12 and 13, over a second guide roll 14, and is finally wound up on a reel 15, which is preferably driven by a slipping belt not shown. The paper may, however, be fed in the form of sheets if desired. As is fully described in the application above referred to, the upper roll 12 is preferably

made of some hard material such as steel, while the lower roll 13 is preferably made of same relatively yielding, elastic material as hard rubber, compressed cotton, compressed paper, etc., capable of withstanding high pressure without excessive deformation at the nip of the rolls. Between the paper and the upper roll passes a belt 16 of suitable finishing material, such as linen, which is carried by rolls 17. One of these rolls is positively driven as by a chain 18 running over a sprocket on the shaft of roll 12; and one is made adjustable, as by a hand screw 19, to keep the belt at all times in a proper condition of tension. Between the paper and the lower pressure roll is a similar belt 20, carried on rolls 21, of which one is driven by a chain 22 from the shaft of roll 13 and one is adjustable by a hand-screw 23. Suitable guides 24, fully described in the application referred to, are provided to direct the belt in a flat condition between the pressure rolls.

The construction of the belts 16 and 20 will now be described; and, as they are exactly similar, a description of one will suffice for both. The belts are preferably made of linen having the pattern it is desired to impress upon the paper, although other fabrics may be used. It will readily be seen that any super-position of layers of the fabric to form a joint would be impossible, as at every revolution of the belt the impression of the joint would be impressed upon the paper. To avoid this, the belt is made of two plies 25 and 26, as shown. One of these plies, as 26, has its two ends trimmed to exactly the right length, and brought into nicely abutting relation. This joining of the ends is preferably done with ply 25, as a backing, the formation of the joint and the securing of the two plies at this point being carried on simultaneously. Great care must be taken in this operation to have the warp threads of the fabric severed cleanly, and the warp threads at each end brought together without any overlap or gap. This joint is denoted in the drawings by 27. The other ply is then laid on and secured by

any suitable adhesive, and its joint made 50 in a similar fashion, but separated or staggered from the joint in the first ply. This second joint is denoted by 28.

The joints 27 and 28 are shown, for illustrative purposes, in the drawings by heavier 55 lines than the lines indicating the weft threads of the fabric. The actual lines of these joints, however, and particularly the joint on the outside ply, or the one presented to the surface of the paper, must be 60 made with extreme care so that the lines of the joint are comparable for all practical purposes with a line of one of the fabric threads. By trimming the ends of the ply with an extremely sharp cutter and by taking care that the abutting ends complement one another without appreciable errors, a joint is produced presenting a smooth, unblemished surface to the paper to be finished, and a belt uniform throughout its entire circumference is insured.

We claim—

1. An endless band adapted for use in machines for finishing paper, comprising a pair of plies adhesively secured together, 75 one of which is composed of fabric having a pattern which is to be reproduced upon the paper, and having a joint therein which is formed by the abutting of the cleanly severed warp threads of the fabric, and the other of which has a joint formed by the abutting of two cleanly severed ends, the two joints being spaced one from another, whereby the paper finished by said band is free from appreciable blemishes reproduced from said joints.

2. A belt for finishing paper presenting a textile surface having a butt joint, the surface configuration of the belt throughout its entire circumference including the butt joint being of such uniformity that no appreciable blemishes are produced in paper finished thereby.

In testimony whereof we have affixed our signatures.

FRANK C. LADD.
